[57] **CLAIM**

The ornamental design for a battery post clamp assembly, as shown and described.

DESCRIPTION

FIG. 1 is a perspective view of a battery post clamp assembly showing my new design. The broken line showing of the battery, cables and additional clamp is included for the purpose of illustrating environmental elements only and forms no part of the claimed design; FIG. 2 is a perspective, top view of my battery post clamp assembly design;

FIG. 3 is a side view of my battery post clamp assembly design, the other side view being a mirror image;

FIG. 4 is a front (away from the cable) view of my battery post clamp assembly design;

FIG. 5 is a rear (towards the cable) view of my battery post clamp assembly design; and,

FIG. 6 is a bottom view of my battery post clamp assembly design.

FIG. 1

FIG. 2

FIG. 4

FIG. 3

FIG. 6

FIG. 5
